UNITED STATES PATENT OFFICE.

JULIA E. ZBOYAN, OF LYONS, NEW JERSEY.

SINK ATTACHMENT.

1,313,153.

Specification of Letters Patent.

Patented Aug. 12, 1919.

Application filed December 14, 1918. Serial No. 266,723.

To all whom it may concern:

Be it known that I, JULIA E. ZBOYAN, a citizen of the United States, residing at Lyons, in the county of Somerset and State 5 of New Jersey, have invented certain new and useful Improvements in Sink Attachments; and I do hereby declare the following to be a full, clear, and exact description of the invention, such as will enable others 10 skilled in the art to which it appertains to make and use the same.

My invention relates to improvements in sink attachments.

An important object of this invention is to 15 provide a sink attachment adapted to be arranged in the drainage pipe of a sink for effectively collecting all refuse from the sink and in such manner as to permit of the ready removal of the same.

20 A further object of the invention is to provide means for conveniently closing the drainage pipe of a sink or basin for permitting of the use of the sink as a receptacle for washing clothes and so forth.

25 A further object of the invention is to provide novel means for supporting a garbage receptacle above the drainage pipe of a sink, thereby permitting of all drainage from the garbage receptacle to fall directly into the 30 drainage pipe.

A further object of the invention is to 35 provide a device of the character described which is easy to apply to sinks of standard construction and is of highly simplified construction.

Other objects and advantages of the invention will be apparent during the course 40 of the following description.

In the accompanying drawings forming a part of this specification, and in which like numerals are employed to designate like 45 parts throughout the same,

Figure 1 is a vertical longitudinal section through my improved sink attachment, showing the same arranged in the drainage pipe of a sink,

Fig. 2 is a side elevation of a garbage receptacle embodied in the invention showing the same supporting a closure for the sink,

50 Fig. 3 is a vertical section through a strainer element embodied in the invention, and,

Fig. 4 is a vertical section through an annular supporting flange embodied in the 55 invention.

In the drawings wherein for the purpose

of illustration is shown the preferred embodiment of my invention, the numeral 10 designates a sink of the usual type and having connection with a drainage pipe 11. An 60 L-shaped annular flange 12 is carried by the bottom of the sink 10 and is disposed within the drainage pipe 11. A strainer element generically designated by the numeral 13 is disposed within the drainage pipe 11 and is 65 connected with the annular flange 12 through the medium of a second L-shaped flange 14. The L-shaped flange 14 is exteriorly screw threaded at its lower portion thereof and has engagement with an annular rim 15 carried 70 by the upper portion of the strainer element. It is thus apparent that the strainer element 13 may readily be removed from the remainder of the structure when desired. The strainer element 13 is provided with an im- 75 perforate bottom 16 adapted to collect all fine particles of refuse and prevent the same from sifting through the screening in the body portion of the strainer element. The upper portion of the annular flange 14 is provided 80 with an annular rim 17 having exterior screw threads engaging the interior screw threads of the annular flange 12. Handles 18 are secured to the annular rim 17 for removing the strainer element 13. A second 85 strainer element generically designated by the numeral 19 is adapted to be arranged in the upper portion of the annular flange 14 and partakes of threaded engagement with the annular rim 17 carried thereby. The 90 strainer element 19 is provided with an annular rim 20 having threaded engagement with the interior of the annular rim 17. A circular piece of mesh wire 21 is arranged in the strainer element 19. A bar or relatively 95 short rod 22 traverses the strainer element and is secured thereto for facilitating the removal of the strainer element 19.

A garbage receptacle 23, clearly shown in Fig. 2, is adapted to be arranged within 100 the upper portion of the annular flange 14 and is provided with a rim 24 having threaded engagement with the annular rim 17. The garbage receptacle 23 is provided with a body portion of mesh wire 25. A rectangular band 26 is secured to the upper portion of the mesh wire 25. As illustrated in Fig. 1, the interior of the receptacle 23 is provided with an annular rim 27 disposed in a horizontal plane with the rim 24. The rim 27 has threaded engagement with a closure 105 28. The closure 28 is provided with a han-

dle 29. It will be apparent that when it is desired to close the sink to function as a wash-tub or the like, the closure 28 may be arranged in position to prevent the discharge of the water from the sink. An arm 5 or T-shaped bracket 30 is carried by the rectangular rim 26 for supporting the closure 28.

In the use of my invention, it will be apparent that as many of the elements as may be desired may be used at one time. For instance, it may be apparent that the strainer element 13 may be readily removed or if desired, the strainer element 19 may be removed. If it is not desired to use the garbage receptacle 23 in conjunction with the remainder of the device, the same may be readily removed.

While I have shown and described the preferred embodiment of my invention, it is understood that I may make such minor changes in arrangement and construction of parts, as will remain within the spirit of the invention, and the scope of the appended claims.

Having thus described my invention, what I claim is:—

1. The combination with a sink having a drainage pipe; an L-shaped annular flange arranged within the drainage pipe; a strainer element arranged within the drainage pipe and having an annular flange having screw threaded engagement with said first named annular flange; a second strainer element arranged within the drainage pipe and having screw threaded engagement with the annular flange of said first named

strainer element, a garbage receptacle carried by the annular flange of said strainer element; and a closure arranged within the garbage receptacle.

40

2. A device of the character described comprising, a strainer element adapted to be arranged within the drainage pipe of a sink, said strainer element having an imperforate bottom and a body portion of mesh wire; an annular flange arranged within the drainage pipe of the sink and having screw threaded engagement with an annular flange of said strainer element, a garbage receptacle having screw threaded engagement with the second named annular flange; and a closure arranged within the garbage receptacle.

45

3. A device of the character described comprising, a cylindrical strainer element adapted to be arranged within the drainage pipe of a sink, said strainer element having an annular flange connected with the upper end thereof; a second annular flange having screw threaded engagement with the annular flange of said strainer element; a second strainer element having screw threaded engagement with the second named annular flange; and a garbage receptacle having screw threaded engagement with the second named annular flange.

55

In testimony whereof I affix my signature in presence of two witnesses.

JULIA E. ZBOYAN.
